MARTIN J. FRANEY, OF SHENANDOAH, PENNSYLVANIA

PERIODICAL HOLDER

Application filed August 8, 1928. Serial No. 298,375.

This invention relates to improvements in periodical holders, reading trays and the like, and has for its main object the provision of a simple and inexpensive holder or tray for 5 periodicals or magazines having soft paper covers, which supports the periodical or magazine in an advantageous and convenient position for reading.

Another object is to provide a holder or 10 tray of the above character, which permits the magazine to be shifted relatively on the holder or tray as the latter is turned bodily so that the successive pages may be read without blocking out that portion of the reading 15 matter contained on the page adjacent the binding.

Another object is to provide a tray or holder of the above character and an associated magazine retention member, with an improved form of connection therebetween.

Another object is the provision of a magazine holder or tray which permits free turning of the pages of the magazine, and further permits positioning of the magazine so that 25 the successive open pages may be easily read.

Other objects will be in part obvious from the annexed drawing and in part indicated from the following analysis of the invention, in which reference is made to the accompanying drawing illustrating one embodiment of 30 my idea.

In this drawing—

Fig. 1 is a perspective view of the periodical holder with a magazine disposed thereon in 35 accordance with my invention.

Fig. 2 is a partial elevation of the magazine folded on the holder, when the left page of the open magazine is to be read.

Fig. 3 is a detail to more clearly portray 40 the arrangement of the tray and magazine retention member.

Fig. 4 is a broken-away elevation, partly in section, illustrating the arrangement of the magazine and holder when the succeeding 45 or right hand page of the folded magazine of Fig. 2 is desired to be read.

Fig. 5 is a modified form of holder.

Referring now to Figs. 1-4 of the drawing, the numeral 10 designates a tray or back- 50 ing sheet of substantially rigid construction

throughout and preferably of rectangular shape. The material of the said tray may be of wood, card-board, metal, fiber composition or the like. Upper and lower indentations 11 are provided along the top and bottom edges 55 of the tray 10 adjacent one side edge, into which is fitted a looped projection 12 of the laterally extending posts 13. The body portion of said posts fits into a slightly undercut edge portion 14, the posts being retained in 60 normally secured position with respect to the tray by flat U-shaped metal clips 15.

An eye or loop 16 is formed at the free end of each post 13, the said eye embracing a bearing member 17 such as a metal ball, 65 which is provided with a central bore 18. The magazine retention member or rack comprises an open frame generally designated 19 and formed of three longitudinal rods, such as the outer rods 20 and the center rod 22 disposed in parallel relation and joined by upper and lower cross rods 21. The center longitudinal rod 22 has an extension 23 at each end thereof, which passes into the bore 18 of the bearing members 17. Such construction permits the frame member 19 to freely rotate about the longitudinal axis of the center rod 22, the said axis being spaced in parallel relation from the side edge of the tray 10, as 70 indicated in Figs. 2 and 4.

Referring to Fig. 1, a periodical or magazine 25 is threaded thru the wire frame 19, the bound portion of the magazine engaging the center rod 22, while the separated body portions of the magazine pass thru the 75 spaces between the end rods 20 and the said center rod. The magazine may of course be opened at any particular page and may be folded back on the tray 10 as indicated in dotted lines, Fig. 1. When the left hand page 80 of the open magazine is to be read, the wire frame 19 is swiveled or rotated about the axis of the journaled center rod 22, and the magazine is bodily shifted laterally with respect to the tray 10 to permit the reading matter at the right hand edge of the page to be 85 read as indicated in Fig. 2. When the next succeeding open page is desired to be read, the magazine and tray are turned bodily in the 90 position shown in Fig. 4, and the magazine 95 100

is shifted laterally on the tray 10 by turning the frame member to thus permit the reading matter at the left hand portion of the page to be clearly viewed.

5 The connection between the posts 13 and the tray 10 permits of ready removal or detachment of these parts when it is desired to insert a new frame member, such for instance of a depth to accommodate different 10 size magazines. In lieu of this actual separation of the said parts, the posts 13 with their spring bends 12 permit the separation of the posts an amount sufficient to insert or withdraw the studs or extensions 23 with respect to the bearing members 17.

Considering now the modified form of the tray illustrated in Fig. 5, the tray 10^a is preferably of metal, and has its upper and lower edge portions turned over a single bent wire 20 comprising the posts 26 and the vertically arranged portion 27. A substantially rectangular frame 28 is provided with loops 30 on its upper and lower cross portions which are disposed about the rod 27, whereby the frame 25 28 is freely rotatable about said rod 27. In this construction, the union of the posts 26 of the single wire frame with the tray may be effected in a single pressing or stamping action.

30 The magazine tray as above described has many uses for the home and reading room and provides advantages in the handling and reading of soft cover magazines or periodicals. Thus, when supported by the tray, a 35 page of the magazine may be maintained in spread-out position in the same manner as a page of a book possessing a stiff back cover, and the tray and magazine may be readily reversed in position to read fully successive 40 open pages.

Inasmuch as the bound portion of the magazine is in a substantially fixed position with respect to the center rod 22 of the frame and also with regard to the end members 20 45 thereof, tearing and loosening of this bound edge is eliminated even tho the magazine is subjected to great handling and rough usage.

Without further analysis of the invention, the foregoing will so fully reveal the gist that 50 others can by applying current knowledge readily adapt it for various applications without omitting certain features that, from the standpoint of the prior art, fairly constitute 55 essential characteristics of the generic or specific aspects of this invention, and, therefore, such adaptations should and are intended to be comprehended within the meaning and range of equivalency of the following claims.

60 I claim:

1. A periodical holder comprising a tray, posts extending along the upper and lower edges and beyond one side edge thereof, and a freely rotatable frame member supported 65 from said posts adjacent the tray, the peri-

odical being threaded thru the frame and extending over the tray.

2. A periodical holder comprising a tray of a substantially rigid material, posts secured along the upper and lower edge of said tray and extending beyond one side edge thereof, and a wire frame thru which the periodical is adapted to be threaded extending between the posts and mounted for free rotatable movement about an axis parallel 70 to said edge of the tray.

3. A periodical holder comprising a tray, posts extending adjacent the upper and lower edges thereof and extending beyond one side edge, means to detachably secure said posts to the tray, and a freely rotatable frame member supported from said posts, the periodical being threaded thru the frame member and extending over the tray. 80

4. A periodical holder comprising a tray having indentations along the upper and lower edges thereof, posts having projections interfitting with said indentations, slips disposed over the posts and tray adapted to maintain said parts in secured relation, and a freely rotatable frame member supported from the posts adjacent the tray. 85

5. A periodical holder comprising a tray, posts secured adjacent the upper and lower edges and extending in parallel relation beyond one side edge thereof, bearing members supported from said posts, and a frame member journaled in said bearing members and mounted for free rotatable movement relative to the tray. 95

6. A periodical holder comprising a tray, posts extending beyond the side edge of the tray, bearing members supported from said posts, and a frame member journaled in said bearing members, said frame member comprising a plurality of longitudinally disposed rods and upper and lower cross rods, one of said rods being extended beyond the cross rods, and journaled in the bearing members. 105

7. A periodical holder comprising a tray, posts extending beyond the side edge of the tray, bearing members supported from said posts, a frame member journaled in said bearing members, said frame member comprising a plurality of longitudinally disposed rods and upper and lower cross rods, one of said rods being extended beyond the cross rods and journaled in the bearing members, and means to detachably secure the posts to the tray. 115

8. A periodical holder comprising a tray having indentations along the upper and lower edges thereof, posts having projections thereon interfitting with said indentations, clips disposed over the posts and tray and adapted to maintain said parts in secure relation, bearing members supported from said posts beyond the side edge of the tray, and 125 130

a frame member mounted for free rotation in
said bearing members.

9. A periodical holder comprising a tray
having indentations along the upper and
lower edges thereof, posts having projec-
tions thereon interfitting with said indentations,
clips disposed over the posts and tray
and adapted to maintain said parts in secured
relation, bearing members supported from
10 said posts beyond the side edge of the tray,
and a frame member comprising a plurality
of longitudinally disposed rods and upper
and lower cross rods, one of said rods being
extended beyond the cross rods and jour-
naled in the bearing members whereby the
frame is freely rotatable with relation to the
tray.

Signed at Atlantic City, New Jersey, this
30th day of July, 1928.
